UNITED STATES PATENT OFFICE.

OSCAR MUSSINAN, JR., OF NEW YORK, ASSIGNOR TO EBERHARD FABER,
OF PORT RICHMOND, NEW YORK.

PENCIL-HOLDER.

SPECIFICATION forming part of Letters Patent No. 368,160, dated August 9, 1887.

Application filed June 2, 1887. Serial No. 240,068. (No model.)

To all whom it may concern:

Be it known that I, OSCAR MUSSINAN, Jr., a citizen of the United States, residing at New York, in the county and State of New York, have 5 invented new and useful Improvements in Pencil-Holders, of which the following is a specification.

This invention relates to improvements in pencil, lead, or crayon holders, as set forth in 10 the following specification and claim and illustrated in the accompanying drawings, in which—

Figure 1 is a section in the plane $x-x$, Fig. 3. Fig. 2 is a section in the plane $y-y$, Fig. 1. 15 Fig. 3 is a plan view of a pencil-holder. Fig. 4 is a view similar to Fig. 3, the clamping-sleeve being removed. Fig. 5 is a perspective view of a modification, part of the device being broken away.

20 Similar letters indicate corresponding parts. In the drawings, the letter A indicates a sheath of wood or other soft material, having slits a at one end. A sleeve, D, is secured in a fixed position on the sheath in rear of the 25 slits, and is provided with an annular projecting bead, constituting a stop, E.

By making the sleeve D of metal or similar suitable material said sleeve will strengthen the sheath A. The free extremity of the slit 30 end is shown as being tapered or conical.

F is a clamping-sleeve formed with a conical end, having a screw-thread, f. Said thread f is adapted to fit over the tapered or conical extremity of the slit end. When the screw-thread f is in firm engagement with said tapered or conical extremity, the slit end will be compressed about the pencil crayon or lead B, as seen in Fig. 1, and said pencil will thus be held securely in place. To release the lead 35 B the screw-thread f is disengaged from the tapered extremity of the slit end and the conical end of the clamping-sleeve is moved away from the slit end C, thus allowing said slit end to relax its hold on the lead. The lead is then 40 free to be moved in the sheath.

A flange, G, on the clamping-sleeve, is adapted to engage the stop E and to prevent the clamping-sleeve from coming off the 45

sheath. Said clamping-sleeve, however, has enough motion on the sheath to clamp or to 50 release the slit end.

A cover, H, such as an india-rubber sleeve, can be provided for the clamping-sleeve F, thus preventing the fingers of the operator from coming into contact with the clamping-sleeve, which may be objectionable in case the sleeve F is formed of metal. By having the screw-thread f at the end of the clamping-sleeve the remaining part of the clamping-sleeve can be made smooth, or provided with 55 ornamental beads I, or given such shape that said sleeve can be agreeably and comfortably held and grasped by the operator. By having the screw-thread f of hard material, such as metal, and the slit end C of soft material, 60 such as wood, said thread f will compress or cut into said slit end, so as to form a screw-thread therein, which screw-thread will conform accurately to the screw-thread f. The labor of forming a screw-thread on the slit end 65 C is thus saved, as such screw-thread will be formed by the application of the thread f to the slit end C while said screw-thread f and said tapered end are in engagement.

I do not broadly claim a wooden sheath having a slitted end, and a clamping-sleeve having a screw-thread engaging said slitted end, as such is not my invention.

What I claim as new, and desire to secure by Letters Patent, is—

The combination, with the sheath A, having the end slits, a, of the sleeve D, secured in a fixed position on the sheath, and having the annular stop E, and the clamping-sleeve F, having at one end the screw-thread f and at 85 the other end the inwardly-projecting flange G, adapted to engage the said annular stop, substantially as and for the purposes described.

In testimony whereof I have hereunto set my hand and seal in the presence of two subscribing witnesses.

O. MUSSINAN, JR. [L.S.]
